CONDIMENT DISPENSER

Efrem M. Ostrowsky, Highland Park, Ill., assignor to Jules P. Gits and Joseph A. Gits, both of River
Forest, Ill.

Application October 10, 1957, Serial No. 48,047

Term of patent 14 years

(Cl. D44—22)

FIG. 1

FIG. 3

Fig. 1 is a plan view of a condiment dispenser embodying my design;

Fig. 2 is a side elevational view of the dispenser of Fig. 1; and

Fig. 3 is a bottom view of the dispenser of Figs. 1 and 2.

I claim:

The ornamental design for a condiment dispenser, as shown.
